US00D962421S

(12) United States Design Patent (10) Patent No.: US D962,421 S
(45) Date of Patent: * Aug. 30, 2022

(54) BREATHING MASK

(71) Applicant: Byoung Woo Kim, Busan (KR)

(72) Inventor: Byoung Woo Kim, Busan (KR)

() Term: 15 Years

(21) Appl. No.: 35/511,311

(22) Filed: Jul. 30, 2020

(80) Hague Agreement Data

Int. Filing Date: Jul. 30, 2020

Int. Reg. No.: DM/209636

Int. Reg. Date: Jul. 30, 2020

Int. Reg. Pub. Date: Feb. 5, 2021

(30) Foreign Application Priority Data

May 27, 2020 (KR) 30-2020-0023509

(51) LOC (13) CI. 29-02

(52) U.S. Cl. ..... USPC D24/110.1

(58) Field of Classification Search

USPC D24/110.1, 112, 130, 110.2–110.4, 127, D24/162, 164; D29/102, 110, 129, D29/104–108; D8/391; D10/124; D11/7, 19, 40, 43, 80; D19/108, D19/115–117; D21/707, 717, 718, 739, D21/840; D22/115, 116; D25/38.1, 42, D25/61, 126–129
